CLAIM

The ornamental design for an LED lamp, as shown and described.

DESCRIPTION

FIG. 1 is a front perspective view of an LED lamp showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof shown in another state;

FIG. 10 is an enlarged view of an oval portion 10 of FIG. 1; and,

FIG. 11 is an enlarged view of an oval portion 11 of FIG. 2. The evenly spaced broken lines in the drawings depict portions of the LED lamp that form no part of the claimed design. The dash-dot broken lines represent boundary lines of the enlarged views and form no part of the claimed design.

1 Claim, 11 Drawing Sheets
